D. P. WITMAN,
SAFETY AIR VALVE,
APPLICATION FILED MAR. 14, 1919.

1,356,579.

Patented Oct. 26, 1920.

FIG. 1

INVENTOR.
DANIEL P WITMAN.

BY
Elie Spear Jr.
ATTORNEY.

UNITED STATES PATENT OFFICE.

DANIEL PAUL WITMAN, OF EAST SOMERVILLE, MASSACHUSETTS.

SAFETY AIR-VALVE.

1,356,579.

Specification of Letters Patent.

Patented Oct. 26, 1920.

Application filed March 14, 1919. Serial No. 282,598.

To all whom it may concern:

Be it known that I, DANIEL P. WITMAN, a citizen of the United States, residing at East Somerville, county of Middlesex, Commonwealth of Massachusetts, have invented certain new and useful Improvements in Safety Air-Valves, of which the following is a specification.

This invention relates to safety air valves for pneumatic drilling machines and the like, and particularly to a valve handle for such a machine. The necessity for an automatic cut-off on such machines is well recognized as eliminating accidents heretofore all too common with the ordinary live air handle usually furnished as standard equipment for such machines.

Valved handles of this type have heretofore been contemplated but such valves have for the most part lacked promptness and certainty of action or have been complicated and liable to disorder.

My present invention contemplates a handle capable of structure both simple and efficient and affording both convenient control and a high factor of safety.

As illustrative of my invention, I have shown as an embodiment a form of handle which I have found highly satisfactory in practical use and which is readily adaptable to all sizes of machines.

In the drawings:

Figure 1 is a central vertical section through the handle.

Fig. 2 a section on the line 2—2, Fig. 1.

Fig. 3 a section on the line 3—3.

Fig. 4 a section on the line 4—4.

In the form shown I have applied a main sleeve or handle body 1 longitudinally bored from end to end. Adjacent to one end the handle 1 is reduced as indicated at 1¹, and surrounded by a rotatable sleeve 2 held in place by the shoulder of a connection 3 which is tapped into the end of the handle.

The reduced portion 1¹ is slotted longitudinally at 4, to receive a pin 5 which projects into a cam slot 6 in the sleeve 2. The pin 5 is tapped into a valve stem 7 which slidably fits within the reduced bore of the portion 1¹. The stem 7 is headed at 8 and seats on a beveled seat 9 opposite to the intake through the connection 3. The valve stem has a double longitudinal channel as at 10 with an intermedial guide pin 10¹ so that the air has practically a direct and straight line admission through the handle of the

tool. The slot 4 is covered at all times by the main body of the stem 7 and the tubular portion 10 which also acts as a guide on the lower end of the stem in its reduced bore. 60 Within the handle portion 1 the longitudinal bore is enlarged for the reception of the safety valve piece indicated at 11. This piece is slidable in the enlarged bore of the handle 1 below the shouldered entry 12 65 against which it is held by the action of a spring 13, which spring normally maintains the valve 11 in the open position shown in Fig. 1, against the seating tendency of the incoming air through connection 3, but 70 which is overcome under certain conditions to permit said valve to close, as will be more particularly disclosed hereinafter. This spring surrounds a hollow stem 14 formed on the connecting nipple 15. The nipple 15 75 has a union connection 16 by which the stem and nipple may be adjustably moved within the handle portion 1 to adjust the compression of the spring 14. The stem 14 is keyed at 17 to the handle against any rotative 80 tendency and is locked by screws 18 seated in slots 19.

The valve 11 is hollow as indicated at 20 having lateral ports 21 and cut away areas 21¹ and is slidably mounted on the end of the 85 stem 14. Within the valve block 11 is the valve 22 and on the end of the stem 14 is a seat 23. The pressure of the spring 13 having been suitably adjusted by the rotation of the connection 19, the machine may be 90 controlled by the rotation of the sleeve 2, raising the valve 8 and admitting air to the machine.

If now the machine be suddenly checked by reason of any stoppage or breakage of a 95 cutting tool a back pressure is built up behind valve 11 and with the incoming air delivers a direct thrust on the large face of the valve block 11, sufficient to overcome the resistance of the spring and close the valve 100 22 firmly on its seat 23. This immediately shuts off the air in time to avoid the jam of the machine with the consequent danger to the workmen.

Various modifications may be made in the 105 structure and operation of my safety handle, all without departing from the spirit of my invention if within the limits of the appended claims.

What I therefore claim and desire to secure by Letters Patent is:

1. A safety handle of the class described

- comprising a body member having an axial air passage therethrough from end to end, a positively operable control and an automatic shut off comprising a tubular valve seat, a hollow enlarged head slidable on said seat, an interior valve on said head and adapted to find said seat and an adjustable resilient support abutting said head for sustaining it against pressure.
- 10 2. A safety handle of the class described comprising a body member having an axial air passage completely therethrough from end to end, a positively operable control adjacent one end of said passage and an automatic shut off adjacent the other end of said passage comprising an enlarged valve head closing with the pressure and having one face formed as a pressure receiving surface constantly exposed directly to said closing pressure in said passage, and its other face formed as a valve, and a seat for said valve and an adjustable resilient support for said head for sustaining it against pressure.
- 15 3. A safety handle of the class described comprising a body member having a central air passage therethrough, a positively operable air control and an automatic shut off comprising a tubular valve seat, a hollow enlarged head slidable on said seat, an interior valve on said head and adapted to find said seat, and a spring coiled about said tubular seat behind said head for sustaining it against pressure.
- 20 4. A safety handle of the class described comprising a tubular body member having a central bore, a rotatable control sleeve adjacent one end thereof, a valve in said bore and controlled by said sleeve, a member in the opposite end of said bore and having a reduced tubular extension projecting within said bore, a valve seat on the inner end of said extension, a hollow valve head slidably mounted on the end of said extension, an internal valve on said head and a spring resiliently supporting said valve head against pressure.
- 25 5. A safety handle of the class described comprising a tubular body member having a central bore, a positively controlled air supply, a valve in said bore, a member adjustably guided in the opposite end of said bore and having a reduced tubular extension projecting within said bore, a valve seat on the inner end of said extension, a hollow valve head slidably mounted on the end of said extension, an internal valve on said head and a spring surrounding said stem and resiliently supporting said valve head against pressure.
- 30 6. A safety handle of the class described comprising a tubular body member having a central bore and externally provided with an enlarged hand hold and a reduced sleeve bearing, a rotatable control sleeve on said
- bearing, a flanged nipple in the end of said bore and retaining said sleeve, a valve in said bore and controlled by said sleeve, a plug member adjustably guided in the opposite end of said bore and having a reduced tubular extension projecting within said bore, a valve seat on the inner end of said extension, a hollow valve head slidably mounted on the end of said extension, an internal valve on said head and a spring surrounding said stem and resiliently supporting said valve head against pressure.
- 35 7. In a device of the class described, a body member having a bore providing an air passage therethrough, a positively operable control, and an automatic shut off comprising a tubular extension projecting into said bore and having a valve seat at its inner end, and a spring controlled valve slidably mounted on said extension and adapted to find said seat.
- 40 8. In a device of the class described, a body member having a bore providing an air passage therethrough, a positively operable control, and an automatic shut off comprising a valve seat, and a spring controlled valve movable relative to said seat and having one face constantly exposed to the pressure through said bore, and its opposite face formed as a valve adapted to find said seat.
- 45 9. In a device of the class described, a body member having a bore providing an air passage therethrough, a positively operable control, and an automatic shut off comprising a tubular extension projecting into said bore and having a valve seat at its inner end, a valve sleeved about said extension and having an internal valve adapted to find said seat, and a spring abutting said valve for sustaining it against pressure.
- 50 10. In combination with a body portion having a bore providing an air passage, a hollow head movable in said passage and having one face formed as a pressure receiving surface constantly exposed to pressure through said bore, and having its opposite face formed as a valve portion.
- 55 11. In combination with a body portion having a bore providing an air passage, a hollow head movable in said passage and having one face formed as a pressure receiving surface constantly exposed to pressure through said bore, and having its opposite face formed as a valve portion, and having a depending skirt surrounding said valve portion and providing a guiding portion.
- 60 12. In testimony whereof I affix my signature in presence of two witnesses.

DANIEL PAUL WITMAN.
